25 LESTER H. MILES

ATTORNEY.

UNITED STATES PATENT OFFICE.

LESTER H. MILES, OF LOS ANGELES, CALIFORNIA.

SIREN AND DRIVING MEANS THEREFOR.

Application filed August 22, 1925. Serial No. 51,884.

This invention relates to sirens.

The general object of the invention is to provide a novel driving means for operating a siren.

A specific object of the invention is to provide means whereby a siren may be driven from the periphery of the fan of a gasoline engine.

Another object of the invention is to provide the mounting for a siren whereby it may be held in position to be driven from the fan wheel of a gasoline engine.

Other objects of the invention will be apparent from the following description taken in connection with the accompanying drawing wherein;

Fig. 1 is a top plan view of a portion of a gasoline engine showing my siren applied thereto;

Fig. 2 is a top plan view partly in section showing the attachment;

Fig. 3 is an end view of the siren, and

Fig. 4 is an end view of the fan wheel.

Referring to the drawing by reference characters, I have shown an engine frame at 10. This frame provides a support for the shaft 11 on which the hub 12 of a fan is mounted. This fan is provided with radial vanes 14 on which a peripheral rim 15 is arranged. The shaft 11 has a pulley 16 thereon which receives a driving belt 17 for the purpose of driving the fan.

Mounted upon the frame 12 is a supporting plate 18 which has a pair of apertures therein to receive fastening studs 19 whereby it may be bolted to the frame.

The supporting plate is provided with a projecting portion 20 which has a boss 21 thereon which is apertured to receive a post 22. This post may be held in adjusted position by means of a lock nut 23.

The siren comprises a stator 24 and a rotor 25 and the stator is provided with a lug 26 thereon. The post 22 has a bracket 27 thereon which has a pair of spaced lugs 28 secured thereto. The lug 26 is arranged between the lugs 28 and these lugs are apertured to receive a shaft 29 which is pinned to the lug 26 and which is free to move in the apertures in the lugs 28.

A spring 30 surrounds the shaft 29 and is fixed to this shaft as shown in Fig. 3. This spring has one end 31 fitted in a recess in one of the lugs 28 and the construction is such that normally the spring tends to turn the stator in one direction.

The siren rotor includes a projecting threaded shaft 33 which has a driving disc 34 thereon. This disc may be made of fibrous material and is arranged between adjustable lock nuts 35 so that it can be moved back and forth.

The projecting portion 20 is so positioned that the disc 34 will be in engagement with the rim 15 of the fan when the siren is in operating position.

In order to move the siren I provide a connection 36 thereon which is connected to a spring 37 and this spring 37 is connected in turn with an operating member 38. The construction is such that normally the spring 30 holds the siren with the disc 34 out of engagement with the rim 15. When the operating member 38 is pulled the siren will be swung about the shaft 29 against the tension of the spring 30 and will bring the disc 34 against the rim 15 to cause rotation of the siren. By including the spring 37 the liability of breakage is reduced to a minimum since this resilient connection will take up a sudden impulse given to the operating member 38 and will thereby remove the strain.

Having thus described my invention, I claim:

1. In combination with a siren including a rotor and a stator, a support for said siren, means to drive said siren; a bracket on said support, said bracket having a pair of spaced lugs thereon, means whereby said bracket may be adjusted to different positions on said support, said stator having a lug thereon adapted to be positioned between said first mentioned lugs, a shaft fitted on said bracket and engaging said spaced lugs and the lug on the stator, a spring normally urging said siren in one direction about said shaft, an operating member and resilient means engaging said operating member for moving the siren against the action of the spring into cooperative relation with said driving means.

2. In a device of the class described, an engine frame, a fan mounted thereon, means for driving said fan, said fan including radial vanes, a rim on said vanes, a siren, means to mount said siren on said engine frame, said means including a projecting plate on the engine frame, an aperture in said projecting plate, a bracket having a post mounted for vertical adjustment in said aperture, said siren including a rotor and

a stator, said bracket having a pair of spaced lugs thereon, said stator having a lug thereon fitted between said first mentioned lugs, a shaft passing through all of 5 said lugs, means to urge said shaft in one direction, said rotor having a friction disc thereon, said disc being mounted adjacent to the periphery of said fan wheel, a spring

for swinging said siren in one direction to contact with the rim of said fan and means 10 for swinging said siren in another direction out of contact therewith.

In testimony whereof, I hereunto affix my signature.

LESTER H. MILES.
